YARN FORWARDING APPARATUS

Robert Duncan McCrosky, Richmond, Va., assignor to E. I. du Pont de Nemours & Company, Wilmington, Del., a corporation of Delaware

Application February 8, 1944, Serial No. 521,587

3 Claims. (Cl. 28—71.5)

This invention relates to yarn forwarding apparatus, and more particularly it relates to an improved construction of yarn forwarding apparatus comprising a feed wheel having peripheral yarn feeding surfaces of increasing diameter from front to rear.

Yarn forwarding apparatus comprising a so-called "stepped" feed wheel, having peripheral yarn feeding surfaces of increasing diameter from front to rear, and a yarn guide roller spaced therefrom are commonly used in the transport of yarn from a spinning bath to a collecting device, for example a spinning bucket. The use of such a stepped feed wheel and spaced guide roller involves an objectionable operational difficulty in positioning the yarn thereon. After the yarn has been passed around the peripheral yarn feeding surface of smaller diameter and about the spaced yarn guide roller, the operator's hand cannot pass to the yarn feeding surface of larger diameter without obstruction by the yarn passing to the said surface of smaller diameter. This necessitates transferring the yarn from one hand to the other and around the yarn passing to the surface of smaller diameter. As the spinning speeds are gradually increased, this becomes a feat which not all operators can perform.

It is therefore an object of this invention to provide a yarn forwarding apparatus comprising a stepped feed wheel and a spaced yarn guide roller which can be easily threaded with one hand.

It is another object of this invention to construct a yarn forwarding apparatus comprising a stepped feed wheel and a spaced yarn guide roller which can be easily threaded without passing the yarn about a previously threaded portion of the yarn.

Other objects of the invention will appear hereinafter.

The above objects can be accomplished by the provision of means for passing yarn to the yarn feeding surface of smallest diameter through the space defined by the peripheral surfaces of the feed wheel and the yarn guide roller and the common tangents to these surfaces.

The present invention can be more readily understood by reference to the following detailed description when taken in connection with the accompanying illustrations, in which:

Figure 1 is a side elevational view of one representative form of yarn forwarding apparatus constructed in accordance with the invention;

Figure 2 is a front elevational view of the apparatus shown in Figure 1;

Figure 3 is a top plan view of the apparatus shown in Figure 1.

Referring to the drawing, reference numeral 6 designates a stepped feed wheel comprising a yarn feeding surface 8 of any given diameter, a yarn feeding surface 10 of a greater diameter than 8, and a beveled flange 12 which is adapted to remove liquid from yarn feeding surface 10 and throw the same, by centrifugal force, into flanged disk 14 from which it may be drained in any desired manner. The feed wheel 6 is driven at any desired peripheral speed through shaft 17. A yarn guide roller 16 is positioned a short distance from the feed wheel 6. The guide roller 16 is usually freely rotatable and yarn driven, and it functions to pass yarn 22 from yarn feeding surface 8 to yarn feeding surface 10. Preferably, roller 16 is so positioned relative to the feed wheel that the yarn passing from surface 8 first contacts flange 19 of the roller (see Figure 2). By first coming in contact with flange 19, the yarn rolls along this flange until it contacts the yarn guide surface of roller 16 and thereby imparts a false twist to the yarn and maintains the yarn filaments in a compact bundle.

Two freely rotatable, grooved yarn guide rollers 18 and 20 are positioned to pass the yarn from its source, for example a spinning bath, to the smaller diameter yarn feeding surface 8 through the space defined by the peripheral surfaces of feed wheel 6 and guide roller 16 and the common tangents to these peripheral surfaces. Guide roller 18 will therefore be positioned at some point rearward of yarn feeding surface 10, and guide roller 20 will be positioned at some point within the above-defined space.

By this construction of guide rollers 16, 18 and 20 and stepped feed wheel 6, the yarn can be threaded onto the yarn forwarding apparatus with one hand in a continuous motion in the following manner: The yarn 22 is passed from its source about guide roller 18, then about guide roller 20, then about yarn guiding surface 8, then about roller guide 16, then about yarn guiding surface 10, and then to its destination as shown by the arrows in Figure 2.

For purposes of clarity and simplicity, the illustrations and the accompanying description are directed to a feed wheel having only two steps, i. e., two yarn contacting surfaces of different diameter, and a cooperating yarn guide roller having a single yarn contacting surface. It is believed to be quite apparent from this description that the feed wheel may have any desired

number of steps and the yarn guide roller 16 may also be provided with a similar series of steps, or a plurality of separate, cooperating yarn guide rollers may be provided to forward the yarn between each two steps of a multi-stepped feed wheel.

Furthermore, by the use of a feed wheel having slightly conical yarn forwarding surfaces and with the axes of the feed wheel and the cooperating yarn guide rollers slightly askew to each other, as shown in the drawing, several wraps of the yarn can be taken about each step of the feed wheel and yarn guide roller.

Since it is obvious that many changes and modifications can be made in the above-described details without departing from the nature and spirit of the invention, it is to be understood that the invention is not to be limited thereto except as set forth in the appended claims.

I claim:

1. Yarn forwarding apparatus comprising a feed wheel having peripheral yarn feeding surfaces of increasing diameter from front to rear, a yarn guide roller spaced from said feed wheel and adapted to guide the yarn from one yarn feeding surface to another yarn feeding surface of greater diameter, and means for passing yarn to the yarn feeding surface of smallest diameter

5 through the space defined by the peripheral surfaces of the wheel and roller and the common tangents to these surfaces.

2. Yarn forwarding apparatus comprising a feed wheel having peripheral yarn feeding surfaces of increasing diameter from front to rear, a yarn guide roller spaced from said feed wheel and adapted to guide the yarn from one yarn feeding surface to another yarn feeding surface of greater diameter, and yarn guide rollers positioned for passing yarn to the yarn feeding surface of smallest diameter through the space defined by the peripheral surfaces of the wheel and roller and the common tangents to these surfaces.

3. Yarn forwarding apparatus comprising a feed wheel having peripheral yarn feeding surfaces of increasing diameter from front to rear, a yarn guide roller spaced from said feed wheel and adapted to guide the yarn from one yarn feeding surface to another yarn feeding surface of greater diameter, and grooved yarn guide rollers positioned for passing yarn to the yarn feeding surface of smallest diameter through the space defined by the peripheral surfaces of the wheel and roller and the common tangents to these surfaces.

ROBERT DUNCAN McCROSKEY.
